CLAIM

The ornamental design for a front section of a portable radio communication device, as shown and described.

DESCRIPTION

FIG. 1 is a front elevational view of a front section of a portable radio communication device showing our new design;

FIG. 2 is a left elevational view thereof;

FIG. 3 is a right elevational view thereof;

FIG. 4 is a top plan view thereof;

FIG. 5 is a bottom plan view thereof;

FIG. 6 is a top, front and left side perspective view thereof; and,

FIG. 7 is a top, front and right side perspective view thereof.

The broken lines shown throughout are included for the purpose of illustrative purposes only and form no part of the claimed design.
